UNITED STATES PATENT OFFICE.

FRANK BILLINGS, OF CLEVELAND, OHIO.

LOADING OR MINING AND LOADING MACHINE.

1,265,730.

Specification of Letters Patent.

Patented May 14, 1918.

Application filed September 3, 1912. Serial No. 718,191.

To all whom it may concern:

Be it known that I, FRANK BILLINGS, a citizen of the United States, residing at Cleveland, in the county of Cuyahoga and State of Ohio, have invented a certain new and useful Improvement in Loading or Mining and Loading Machines, of which the following is a full, clear, and exact description.

10 This invention relates to a machine adapted primarily for loading or mining and loading purposes.

The machine forming the subject matter of my present invention is of the general type disclosed in my prior application, filed January 17th, 1910, Serial No. 538,408, and it includes in combination with some suitable form of conveyer or material conveying means, an operative member in the form of 20 a ram or beam suitably mounted so that it may be given a variety of movements required to convey material expeditiously to the conveying means and suitably constructed not only to facilitate the handling of 25 the material but to adapt this ram for a variety of other purposes incidental to the collection, moving and loading of the material. Further, the invention aims to provide in a machine of this character a ram 30 adapted to be equipped with any one of a number of tools which may be utilized in the mining or loading process; to so construct, arrange and operate the parts that the ram can be moved about, reversed and 35 may have applied to it variable degrees of power, in any direction within the limits of the machine very quickly by giving to the ram power to produce different movements successively, or simultaneously, if desired; 40 and to provide a machine having flexibility in speed and power, and such other characteristics as are required for a very highly efficient machine of this character.

The invention may be here briefly summarized as consisting in certain novel combinations and arrangements of parts, as well as numerous details of construction which will be described in the specification and set forth in the appended claims.

50 While my invention in its broad aspects is susceptible of numerous modifications in construction and in the manner of mounting and operating the parts to obtain certain movements and functions, I have in the

drawings shown one embodiment of the 55 main part of the machine which answers the requirements very effectively, and in the drawings Figure 1 is a side elevation of the forward portion of the machine with parts broken away. Fig. 2 is a top plan view of 60 the same. Fig. 3 is a rear elevation of the main operative parts of the machine with the conveyer and main frame in transverse section, parts being broken away for the sake of clearness. Fig. 3^a is a fragmentary 65 top plan view showing a modification of the hoe adjusting means. Fig. 4 is a top plan view of the outer end of the ram showing the universal tool head or holder. Fig. 5 is a side view of the same. Fig. 6 is an end 70 view of the same. Fig. 7 is a top plan view of the same on a slightly reduced scale, with the universal tool holder equipped with a picking tool. Fig. 8 is a similar view of 75 the end of the ram with the tool holder equipped with a hammering tool. Fig. 9 is a side elevation of the outer end of the ram with the tool holder equipped with a relatively fixed hoe or scraper. Fig. 10 is a top plan view of the outer end of the ram 80 showing the tool holder equipped with a modified form of picking tool. Fig. 11 is a side elevation of the outer end of the ram with the tool holder equipped with a shovel, the dotted lines showing the different positions of the shovel and showing a conveyer 85 with which the shovel may coöperate. Fig. 12 is a more or less diagrammatic view showing the system of control utilized in connection with the different motors.

90 The machine is adapted to run upon the rails of a track 10, and includes a rigid frame 11 which extends longitudinally of the machine and which is supported from the rails by suitable wheel trucks, a portion of one of which is shown at 12. The machine is also provided with some form of conveyer for conveying material rearwardly from the front end of the machine, and in the drawings I have shown an endless belt conveyer 13 which extends from the front of the machine rearwardly. At the forward end of the conveyer 13, I have provided an inclined apron 14, along which the material is adapted to be moved by the apparatus 100 hereinafter described, and deposited into a suitable hopper 15, (see Fig. 3), which is arranged over the forward end of the con- 105

veyer so that material deposited in the hopper will drop immediately on the conveyer belt and be carried rearwardly. I have not considered it necessary to show the entire frame or the entire conveyer, or more of the details of the apron and hopper, as these parts may have any suitable construction which answers the requirements of such a machine.

10 The machine is provided at its forward end and above the conveyer with a substantially horizontal supporting member 16 which is supported from both sides of the frame 11, as best shown in Fig. 3, so as to leave sufficient space between the support 16 and the upper run of the belt of the conveyer to permit large lumps of material, such as coal or rock, to be handled by the conveyer without interference by and without engaging this superstructure. Swiveled by a central king bolt 17 (see Fig. 2), to the horizontal support 16, and rotatably supported thereon through the medium of a series of rollers 18 which engage a circular track of the support 16 is a turn table 19 upon which is directly or indirectly supported much of the apparatus of the machine, and which is rotated by means herein-after described about the vertical axis of the king bolt to impart a certain horizontal swinging movement to the ram and to the tool carried thereby.

Extending upwardly from the turn table 19 are suitable brackets and bearings 20 which support a horizontal shaft 20^a (see Figs. 1 and 3), to which is secured for rocking movement about the horizontal axis of said shaft, a cradle or housing 21. This housing supports a reciprocating telescopic ram 22 composed in this case of an outer box-like member 22^a adapted to slide backwardly and forwardly through the housing, and an inner ram member 22^b adapted to telescope with or to move in or out of the member 22^a as the latter is moved in or out with respect to the housing. The outer member of the ram is supported from the housing through a series of rollers 23 which bear against the top and bottom sides of the outer ram member, and the housing is also provided with guide rollers 24 which engage the sides of the member 22^a. The outer ram member 22^a is provided with a series of rollers 25 which engage the top and bottom sides of the inner ram member 22^b and support the same, and also with guide rollers 26 which engage the sides of the inner ram member 22^b. The housing 21 has a forwardly projecting arm 27 provided on its lower side with a rack 28. Rotatably supported in the upper part of the outer ram member 22^a beneath the rack 28 is a pinion 29 which engages the rack 28 and also engages a rack 30 mounted upon the top of the inner ram member 22^b below said pin-

ion. By reason of this construction, when the outer ram member is reciprocated in the housing, the pinion is rotated because of its engagement with the relatively fixed rack 28, and as the rotation of this pinion is 70 transmitted to the rack 30, the inner ram member is at the same time reciprocated with respect to the outer ram member and the telescoping action is obtained.

For controlling the movements of the 75 ram, I prefer to employ for reasons herein-after referred to, three separate fluid-pressure reciprocating motors. For swinging the ram horizontally about the vertical axis of the turn table, I employ a fluid pressure 80 motor 31, which includes a cylinder 31^a mounted on the turn table and containing a piston (not shown) connected to a plunger 31^b. This plunger is attached to a rack 32 (see Figs. 1 and 2) which engages a 85 pinion 33 secured to a short vertical shaft, to the lower end of which is secured a larger pinion 34, which engages a section of a circular rack 35 fixed to the base or support 16.

For swinging the ram in a vertical plane, I employ a motor 36 which includes a cylinder 36^a supported upon brackets 37 extending upwardly from the turn table 19 (see Fig. 3), and a piston (not shown) 95 which is connected to a plunger 36^b having at its outer end a journal box which receives a wrist pin connected to a pair of crank arms 38, (see Fig. 3), secured to the shaft 20^a upon which the housing 21 is mounted.

For reciprocating the telescopic ram relative to the housing I employ a fluid pressure motor 39 comprising a cylinder 39^a which is supported upon the housing 21, and a piston (not shown) connected to a 105 plunger 39^b, the forward end of which is connected to the forward end of the outer ram member 22^a. The motors 31, 36, and 39 are preferably air motors, the supply to and exhaust of air from which may be controlled by suitable valves properly located with reference to the operator's station 40, (see Fig. 2), as will be explained more fully in connection with Fig. 12.

There are numerous advantages derived 115 from the use of separate motors and particularly fluid pressure reciprocating motors connected to the ram as shown and described, the chief of which are speed of ram operation, reversibility, ability to give to 120 the ram its reciprocating, horizontally swinging or vertically swinging or rocking movements separately, or a combination of movements simultaneously; flexibility in 125 speed and power, by which I am enabled to impart to the ram through the proper control of the valves, fast or slow movements, short or long strokes and powerful or light strokes. These advantages enable me to 130 utilize the ram not only for material scrap-

ing or collecting purposes, but also for a variety of other purposes, including chipping, picking, hammering or shoveling,—all of which functions are of utility, especially for mining purposes, wherein the machine can be utilized for loosening the material, for leveling and truing the floor and walls, for driving wedges and other devices, and for similar purposes.

- 10 To adapt the machine for these numerous functions, I provide on the outer end of the ram what may be termed a universal tool head or holder 41, which preferably embodies a forwardly projecting boss 41^a and a cylindrical socket or passageway 41^b extending through the end of the tool head at right angles to the boss, and provided with a key way 41^c. This construction is shown most clearly in Figs. 4, 5 and 6.
- 15 In Fig. 7 the tool holder is provided with a picking or ramming tool 42 which is secured to the boss 41^a and which is adapted when the ram is thrust forwardly to loosen material.

- 20 In Fig. 8, the tool holder is provided with a hammer 43 which is secured in a suitable manner to the boss 41^a.

In Fig. 10, the ram is provided with a pick which is secured to the boss 41^a so that the material may be loosened as it would be by an ordinary manually handled pick. This pick can be fixed in any angle so as to loosen the material when the ram is swung vertically, horizontally, or is given a combination of the two movements.

In Fig. 11, the ram is provided with a scoop shovel 45 which is filled by moving the ram forwardly, or simultaneously forwardly and upwardly, and is dumped by moving the bucket rearwardly. This bucket has digging teeth 45^a, at its forward end and is provided with a swinging bottom 45^b, adapted to be dropped or released by a latch 45^c operated in any suitable manner. This bucket is held to the tool head of the ram by a U-shaped device 45^d secured to the bucket and having an opening for the boss 41^a of the head, and having rearwardly extending ears through which and through the opening 41^b of the tool head a bolt or stud 45^e passes.

In Figs. 1 and 9, I have shown, however, the principal tool intended to be employed with the ram, this tool consisting of a hoe 46, the function of the hoe being to scrape the material rearwardly to the conveyer. The hoe 46 may be fixed in position on the end of the ram, as shown in Fig. 9, wherein the hoe is secured to a casting 47, which in turn is secured to the tool head by means of a bolt 47^a which passes through and is keyed in the socket 41^b of the tool head, and is provided at its upper end with a tightening nut 47^b. When the ram is provided with a fixed hoe, as shown in Fig. 9, the

material is scraped back onto the conveyer by reciprocating the hoe shank, and by giving it other necessary movements. When the material is located at one side of the plane of the apron, the material may be moved onto the conveyer by simultaneously moving the hoe and ram (after the hoe has been sunk into the material) laterally or toward the center line of the machine, as well as rearwardly.

Very often, however, this construction will not answer all the requirements for effective work, especially when the machine is intended to work through a wide angle, and material must be brought into line with the machine from the sides thereof. In such event, it may be desirable to scrape a considerable quantity of material from the sides of the passageway made or cleared by the loading machine, laterally to or toward the center line of the machine before such material is moved rearwardly onto the conveyer. The edge of the hoe if fixed on the end of the ram would not be entirely suitable for this purpose. I have therefore provided a construction which is shown in Figs. 1, 2 and 3 wherein the operator may turn the hoe so as to present substantially the flat face of the hoe to the material when the material is moved laterally toward the center line of the machine by swinging the ram laterally. For the purpose of turning the hoe I provide, reasonably close to the operator's seat, a hand wheel or equivalent turning device 50, connected by a spline to a sectional telescoping rod or shaft 51 which is supported by suitable brackets from the ram and housing. The outer end of this shaft is provided with a worm 52, which engages a worm wheel 53 fixed to the bolt or spindle 54 to which the casting 47 carrying the hoe 46 is fixed. The worm wheel and worm may be supported from the outer end of the ram in any suitable manner, but in this case, I have secured by bolts 55 to the top face 110 of the universal tool head 41, a standard 56, through which the spindle 54 passes.

Instead of turning the hoe by hand I may employ a suitably controlled motor for this purpose. In Fig. 3^a this is shown in plan view wherein I employ for adjusting the hoe a fluid pressure motor 50^a which is mounted on cylinder 39^a of motor 39 and is connected by gearing 50^b to shaft 51 which extends forwardly to the outer rod of the ram as shown in Figs. 1 and 2.

In some instances, it may be desirable when the hoe is extended a certain distance to hold the reciprocating mechanism against movement while other movements are imparted to the ram such as when the ram is used for digging, picking or hammering purposes. I therefore provide a lock for the reciprocating mechanism consisting of a sliding locking bolt 58 upon the top of 180

the outer ram section 22* and adapted to be extended between the teeth of the pinion 29 and to lock the same, and hence the entire reciprocating mechanism, against movement.

5 Likewise it may be desirable when the ram has been tilted vertically to a certain angle with respect to a horizontal plane to lock the tilting mechanism so as to maintain the ram at that angle while other movements may be imparted thereto. I therefore provide a lock for the tilting mechanism, which consists in this case of a toothed segment 57 secured to the shaft 21 upon which the housing is supported, and about 15 which the hammer is tilted, and a pivoted locking arm 58 having a locking nose adapted to be inserted between two adjacent teeth of this segment.

Inasmuch as it may be also desirable to 20 swing the ram laterally to a certain angular position with reference to the vertical plane passing through the axis of horizontal swinging movement of the ram, and to lock the ram against further lateral swinging 25 movement, I have provided for this purpose a locking means which in this case consists of a pair of arms or latches 60, (best shown in Fig. 2), which latches are suitably supported with reference to the rack 32 so that 30 the nose of one or the other of said latches may be inserted between any two of the teeth of the rack to hold the rack against further reciprocating movement, and to prevent rotation of the pinion 33. I have provided two such latches so that the rack may 35 be locked against movement regardless of its position with reference to the cylinder of the corresponding motor.

In order that the machine may be utilized 40 for the various purposes referred to, and in order that the ram may have the functions above described, it is of course essential that the ram be capable not only of being thrust laterally outwardly, inwardly, downwardly, 45 or upwardly by the several motors, but the ram must be capable of successfully resisting stresses, both in horizontal and vertical planes, incident to the shocks which would result from hammering, picking and other 50 operation, and from driving or sinking the hoe into a mass of material preparatory to moving it onto the conveyer. This is provided by constructing and supporting the ram so that it will be capable of successively 55 resisting any of the stresses, to which the ram may be subjected in the use of the machine.

I have previously mentioned the fact that the machine for successfully performing the 60 functions for which it is intended, should be so constructed and operated that a combination of separate movements could be imparted to the ram simultaneously. That this characteristic is desirable if speed of 65 operation and good results are to be ob-

tained is apparent when it is considered that the operator is thereby enabled to move the hoe outwardly and simultaneously elevate the same, or simultaneously outwardly, upwardly and laterally. Thence when the 70

hoe has been sunk into a mass of material by giving the hoe, if necessary, a quick sharp downward thrust, material can be moved back onto the conveyer by moving the hoe rearwardly or simultaneously rear-

75

wardly and laterally (in the event that the material is at one side of the machine) and at the same time force can be exerted downwardly on the hoe by admitting the right pressure of air to the rear of the 80 piston of the motor utilized in elevating the hoe, to prevent the hoe being elevated, or by itself shifting upwardly, as the heavy mass of material is drawn rearwardly.

85

The desirability of simultaneously applying two movements to the hoe, or of applying power to the ram through two cylinders, is clearly illustrated while the hoe is in the act of drawing a mass of material to the conveyer. In case a mass of material 90 is being drawn by the hoe, say along the floor of the mine, or along any surface, and in case an obstruction is reached, instead of stopping or obstructing the passage of the hoe (as would be the case if 95 the operator did not have complete and instant control for movement in all directions) to avoid such obstruction, the operator has simply to lift the hoe slightly over the same without stopping its rearward 100 movement and then to lower the hoe again when said obstruction is passed. If only one movement could be imparted to the hoe at one time, it would be necessary for the operator to stop the rearward movement before moving the hoe over the obstruction, then move the hoe rearwardly again, thence stop it, thence lower the hoe, and thence again continue the rearward movement.

105

At this point it may be well to describe 110 an important detail of my invention, which is of particular utility when the machine is used in a mine where it is desirable that the mine floor be left by the hoe in even or flat condition. This feature which I have 115 just referred to consists of an arrangement by which the hoe is caused to travel rearwardly, in moving material onto the conveyer, in a straight line, and is prevented from leaving the floor in an uneven condition by being depressed more than a certain amount and cutting into the floor level. It will be seen by reference particularly to Figs. 1 and 2, that the rear part of the outer ram member 22* is provided with a roller 120 62, and that the housing is provided above this roller with a curved angle member 63, which serves as a guide for the roller and as means for controlling the path of movement of the bottom of the hoe, as the same is 125 130

5 moved rearwardly. The curve of the member 63 is such that as the hoe is moved rearwardly, its downward inclination is increased at the proper rate to cause the bottom edge of the hoe to move in a straight line and to prevent it from being depressed beyond said straight line. When the hoe reaches the forward end of the apron, the roller passes beyond the member 63 and 10 thence moves in a straight line, inasmuch as the hoe is constrained to thence move in a direction parallel to the face of the apron, and just out of contact therewith, the hoe then being tilted downwardly the maximum 15 amount permitted by the stroke of the tilting motor. The turn table is also preferably provided with an L-shaped track 64 which is engaged by the roller 62, when the ram and hoe arm are moved rearwardly 20 with the ram elevated. This guide track 64 gradually decreases the inclination of the ram as it is moved rearwardly, and thus prevents the rear end of the ram colliding with the turn table.

25 Reference is now had to Fig. 12, wherein I have illustrated diagrammatically a system of control by which the variable characteristics of speed, power and length of stroke may be obtained. As before stated, I utilize 30 fluid pressure reciprocating motors, preferably, however, air motors. Assuming that air is a motive fluid, the air is supplied under suitable pressure through a supply pipe 70 which is connected by piping designated as a whole by the reference figure 71 to three four-way valves 72, 73 and 74, one of which is associated with each of the three fluid pressure motors, 31, 36 and 39, and is adapted to control the application of power to that motor, and hence to control the speed, power and length of stroke imparted to the ram by means of such motor. The four-way valve 72 has an operative handle 72^a, and in addition to the inlet pipe connection 45 has an exhaust pipe 72^b, and has also connected to it two air conveying pipes 72^c and 72^d which are connected to the cylinder of motor 31 near the ends of said cylinder. By properly manipulating the valve member 72^a air may be conveyed through the pipe 72^c to the rear of the piston of motor 31, and exhausted or carried away from the forward end of the motor (in advance of said piston) through the pipe 72^d, so as to 50 drive the piston forwardly, or air may be supplied through the pipe 72^c and exhausted through the pipe 72^d, and exhaust pipe 72^b, so as to drive the piston rearwardly. In a similar manner four-way valve 73 has an 55 operating handle 73^a, an exhaust pipe 73^b and two air conveying pipes 73^c and 73^d which are connected to the cylinder of motor 36, and four-way valve 74 has an operating handle 74^a, and exhaust pipe 74^b and 60 two air conveying pipes 74^c and 74^d, which

are connected to the cylinder of motor 39 near the forward and rear ends thereof.

With this system of control employed in connection with the fluid pressure reciprocating motors, not only is there flexible 70 speed and power obtainable, and not only can different movements be imparted to the ram simultaneously, and variable degrees of power applied thereto at one or a plurality of points, but I am enabled to stop and start 75 any ram movement or reverse the movement of the ram very quickly.

Having thus described my invention, what I claim is:

1. In a machine of the character described, a wheeled frame adapted to run along a track, and provided at its lower front end with a material receiving element into which material is adapted to be deposited, a ram formed to resist heavy stresses 80 transversely and longitudinally extending from the forward end of the machine, said ram adapted to be provided at its forward end with a working tool, said ram being mounted on the frame for reciprocating movements forwardly and rearwardly with the working tool traveling at a variable height substantially down to the plane of the track, and for swinging movements laterally to either side of the machine and vertically from a plane above the center of the machine to substantially the plane of the track, and means for imparting to said ram in any of said directions and between any of the limits stated movements of a gradual 90 character or rapid strokes or blows whereby 95 said ram may be employed for scraping material toward the frame or for delivering picking or hammering blows to material to be loosened or broken.

2. In a mining machine of the character described, a wheeled frame adapted to run along a track, and provided at its lower front end with a material receiving element into which material is adapted to be deposited, a ram formed to resist heavy 100 stresses transversely and longitudinally projecting from the end of the frame and adapted to be provided at its forward end with a working tool, said ram being 105 mounted on the frame for reciprocating movements forwardly and rearwardly with the working tool traveling at a variable height substantially down to the plane of the track, and for swinging movements laterally to either side of the machine, and vertically from a plane above the center of the machine to substantially the plane of the track, and motive means operatively connected to said ram for imparting thereto 110 strokes of variable length and power in any of said directions and between the limits stated whereby 115 said ram may be given sharp, quick strokes to impart breaking, picking or hammering blows to material.

- 6
3. In a mining machine, a wheeled frame adapted to run along a mine track and provided at its forward end with a material receiving element, a ram formed to resist heavy transverse and longitudinal stresses and projecting from the forward end of the frame, said ram adapted to be provided on its forward end with a working tool, a turn table mounted on the frame for rocking movement about a vertical axis, a cradle mounted on the turntable for rocking movement about a horizontal axis, said cradle receiving said ram, and motive means operatively connected to the ram, cradle and turntable for actually the said parts so as to impart to the ram strokes of variable speed, length and power forwardly and rearwardly with the working tool traveling at a variable height which may be as low as the track and strokes, laterally to either side of the machine, and vertically from a plane above the center of the machine to substantially the plane of the track, whereby said ram may be given sharp, quick strokes in any of said directions and between the limits stated, enabling the ram to be used for picking, hammering or material breaking purposes, or enabling the same to be given relatively slow movements so as to move loosened material toward the frame.
4. In a loading machine, a frame provided at its lower front end with a material receiving element, means for moving material laterally and rearwardly, comprising a hoe shank movably supported by the frame; a hoe supported on the shank so that it may be set or fixed at widely different angles with respect to the shank, and an adjusting member connected to the hoe for varying the angle of the hoe and for holding the same in any desired angular position with respect to the shank so that it will face in the direction the material is being moved whether the material is moved laterally or rearwardly.
5. In a loading machine, a frame, means for moving material laterally and rearwardly comprising a hoe shank movably supported by the frame, a hoe movably supported on the shank, and adjusting means connected to the hoe and controllable from a point at the rear of the hoe, for moving the hoe so that it will make any desired angle with the shank and so that it will be held to face in the direction the material is being moved, whether the material is moved laterally or rearwardly.
6. In a loading machine, a frame, a material receiving element at the lower front end of the frame, a hoe shank supported by the frame and mounted for movement in various directions, means for swinging the hoe shank vertically and for reciprocating the shank, a hoe carried by the shank and co-operating guide members for controlling the path of movement of the hoe when the latter is scraping material rearwardly toward the material receiving element.
7. In a loading machine, a frame, a hoe shank movably supported by the frame, a hoe carried by the shank, means for swinging the shank vertically and means for reciprocating the shank, and a pair of co-operating guide members one movable with the shank and the other fixed relative thereto for causing the hoe to move through a predetermined path when scraping material rearwardly toward the frame.
8. In a loading machine, a frame; a housing supported by said frame for rocking movement about a substantially horizontal axis, a ram mounted for reciprocating movement in said housing, means for rocking the housing and for reciprocating the ram, and guiding means for the ram comprising a member movable with the ram and co-operating with a relatively fixed part for gradually increasing the inclination of the ram as the ram is moved rearwardly in the housing when inclined upwardly.
9. In a loading machine, a wheeled frame having at its lower front end an upwardly inclined apron and having a conveyer which extends from the apron lengthwise through the frame, a ram adapted to be provided at its forward end with a working tool and formed to resist stresses transversely and longitudinally, said ram extending forwardly from the machine, and being mounted on the frame for reciprocating movements forwardly, and rearwardly to substantially the rear end of the apron with the working tool traveling at a variable height substantially down to the plane or surface over which the machine is adapted to be run, also mounted for swinging movements laterally to either side of the machine and for swinging movements vertically from a plane above the center of the machine down substantially to the plane or surface over which the machine is adapted to run, and means for imparting to said ram in any of said directions and between any of the limits stated, movements of a gradual character, or rapid strokes or blows whereby the ram may be employed for scraping material along a surface beneath the conveyer toward the frame and up the apron to the conveyer, or for delivering picking or hammering blows to material to be loosened or broken, said means comprising a plurality of fluid pressure motors, one of which is directly connected to the ram.
10. In a loading machine, a wheeled frame provided at its forward end with an upwardly inclined apron and having a conveyer which extends from the apron lengthwise through the frame, a turntable mounted on the frame for rocking movement about a vertical axis, a cradle mounted on the turn-

table for rocking movement about a horizontal axis, a ram mounted to reciprocate in the cradle and adapted to be provided at its forward end with a working tool, said parts being so arranged that the ram may be moved forwardly and rearwardly with the rearward limit of movement substantially at the rear end of the apron and that the ram may be swung laterally to either side of the machine and may be swung vertically from a plane above the center of the machine down substantially to the plane or surface over which the machine is adapted to be run, fluid pressure motors, one connected to the turntable, one to the cradle, and one to the ram, and means for controlling said motors so that the latter may impart to the ram strokes of variable speed, length and power, forwardly and rearwardly, with the work-

ing tool traveling at a variable height which may be as low as the surface or plane over which the machine is adapted to be run, and laterally and vertically, whereby said ram may be given sharp quick strokes in any of said directions and between the limits stated, enabling the ram to be used for picking, hammering, or material breaking purposes, or whereby said ram may be given relatively slow movements so that loosened material may be scraped rearwardly toward the frame and up the apron to the conveyer.

In testimony whereof, I hereunto affix my signature in the presence of two witnesses.

FRANK BILLINGS.
